MACHINE AND METHOD FOR PROCESSING WEBS OF PAPER BASE AND SIMILAR MATERIALS

Earl A. Crawford, Providence, R. I., assignor to Bird & Son, Inc., East Walpole, Mass., a corporation of Massachusetts

Application April 29, 1953, Serial No. 351,970

12 Claims. (Cl. 101—181)

The present invention relates to an improved machine and method for continuously feeding and for processing webbed materials.

More specifically the invention relates to a printing machine and method which is adapted for placing, in registered relation with one another, successive accurately registered impressions upon a webbed material of the general type having a limited stretch characteristic which is impregnated with asphalt or which is formed on a paper base.

The invention is herein disclosed in a preferred form as embodied in a machine and method for roller printing, coating or otherwise processing a webbed material suitable for use as floor and wall coverings, and the like which is formed from a paper base or from a web impregnated with asphalt and having a limited stretch characteristic.

In the development of a machine of the general type referred to having a plurality of roller printing units which are related to one another for the printing of recurring designs of varying shapes and colors, serious difficulties have been encountered in controlling the feed of the webbing to insure the accurate register of successively applied impressions thereon.

It is a principal object of the invention to provide a machine and method for supporting and for feeding webbed material of this general description to successive printing stations in such a manner that the position of the web both lengthwise and widthwise may be accurately controlled at each printing station in turn to insure an accurate register of successive impressions upon the material.

It is a further object of the invention to provide a means and method of controlling the feed of a webbed material which may, for example, be a floor covering material having a thickness of from .04" to .06", passing continuously over a roller conveyor in such a manner as to cause the material to travel as a dead sheet without any tendency to stretch or to weave laterally during a run of substantial length past a plurality of roller printing units.

It is a further object of the invention to combine with a conveyor system of this general description a plurality of roller printing units which are well adapted for the continuous high speed application of successive impressions to the strip material at their respective printing stations along the length of said run, the construction and arrangement of these devices being further adapted to cause the several impressions to be at all times accurately registered with one another and with the webbed material passing through the conveyor.

In carrying out the invention, a method of conveying a webbed material as a dead sheet along a substantial run past a plurality of printing units is provided, which comprises the steps of supporting the webbed material at the two ends of the run between positively driven pairs of draw-in and draw-off driving rollers, driving the draw-off rollers at a predetermined rate to draw the sheet along the length of the run, and driving the draw-in rollers,

2

stationed at the beginning of the run, at a slower rate which is controlled in such a manner as to produce a drag or tension of a predetermined amount upon the webbed material passing across the run.

5 Specifically, in accordance with the invention the draw-off rollers and the rollers of each printing unit are driven at the same linear rate, while the draw-in rollers are driven at a slower rate, which is automatically adjusted to produce a retarding tension or drag which is within the elastic limit of the webbed material, but which will cause a sufficient stretch of the material to take place so that the material then travels as a dead sheet along the length of the run through the printing units to the draw-off rollers.

10 It is a still further object of the invention to provide a novel printing unit for use in a machine of the type herein described, in which a traveling web 12 feet more or less in width is passed in a substantially horizontal straight line through the printing unit which comprises an organization of the several printing and support rollers which will have a maximum strength and rigidity for imparting an even impression across the width of the webbed material.

15 It is another object of the invention to provide a printing device of this general description which is well adapted for the application of ink impressions to the upwardly facing side of the traveling strip material.

20 It is another object of the invention to provide in a printing unit of the general type shown a novel and improved means for supplying ink to and for scraping excess ink evenly from the gravure roller along its length across the width of the traveling web.

25 It is a further object of the invention to provide in a machine of the general type described having a draw-in roller unit, a draw-off roller unit, and a plurality of printing units spaced therebetween for imparting successive impressions to a traveling strip of webbed material, a novel and improved means capable of manual or automatic operation for correcting the register of the individual printing units with relation to the feeding strip, and with relation to one another both laterally and longitudinally during the continuing uninterrupted operation of the machine.

30 It is still another object of the invention to provide a novel means well adapted for use in a machine of the type herein described for rendering the printing mechanism inoperative without at the same time interfering with the feeding of the webbed material through the machine.

35 The multiple unit web printing machine particularly illustrated and described as embodying in a preferred form the several features of the invention, comprises generally a series of four units having pairs of cooperating drive support and pressure rollers or cylinders through which the webbed material is passed in a straight line run. The webbed material is drawn into the machine by the draw-in unit, passes through a first printing unit with its associated drying oven, through a second printing unit with its associated drying oven, and is then finally discharged from the printing machine through a draw-off unit.

40 An outstanding feature of the present machine consists in the construction and arrangement of the several units to provide a straight line run of the webbed material through the printing machine which is thus well adapted to form an integral part of a continuously operating production line for the coating and finishing of webbed floor covering and similar materials.

45 Difficulties have long been experienced in controlling the feed of a web having a paper or asphalt saturated base and adapted for use as a wall or floor covering, for the reason that the material tends to be of somewhat

uneven quality, does not have any great degree of tensile or tearing strength, and when mounted on a roller conveyor tends to feed unevenly and also to weave from side to side. A feature of the invention consists in the provision of means for controlling the feed of a web of this general description along the length of a substantial run in such a manner that no deviation either lengthwise or laterally of the web will be encountered along the length of the run, thus making possible the application of successive printing impressions to the face of the material in accurately registered relation to one another. Applicant has found that a carefully regulated tension or drag applied to the webbed material at the beginning of the run can be employed to stretch the material within its elastic limit to entirely eliminate any tendency of the material to stretch or weave while passing through a series of printing units which may be two or more in number, spaced along the length of the run. It has been found further that all of the stretch introduced into the material by the tension or drag, referred to, takes place at the beginning of the run so that the web travels substantially the entire length of the run as a dead sheet.

In accordance with the invention a driving mechanism is provided which is well adapted for driving the cooperating driving support and pressure rollers in each of the draw-off units and the several printing units of the printing machine at the same linear rate while the driving support and pressure rollers of the draw-in unit tend to be driven at a slower rate so that the web is subjected to a braking tension or drag while passing through the initial draw-in unit. The mechanism provided for imposing a drag upon the feeding web at the location of the draw-in unit consists in a differential connection in the draw-in support roller drive, and a torque motor which acts through the differential connection to reduce the rate of drive of the draw-in drive support roller and thereby to exert a drag upon the feeding web. The pressure exerted through this mechanism is regulated to produce an amount of stretch in the web of floor covering material sufficient to remove substantially all stretch from the material within the elastic limit. The amount of resistance or drag imposed on the feeding strip is controlled manually through the adjustment of electrical means connected to the torque motor.

In accordance with the invention it is proposed that adjustment of the retarding tension or drag employed will be made by the operator. The adjustment is simply made by increasing the retarding tension or drag and consequent stretch gradually to a point where the material runs as a dead sheet and without exhibiting any tendency toward weaving or stretching. Experience has shown that the amount of drag required will be that required to remove substantially all of the stretch of which the material is capable but preferably without exceeding its elastic limits.

A feature of the invention consists in the construction and arrangement of the several operating units to permit the simultaneous movement of each of the driving support rollers out of engagement with the cooperating pressure rollers thus to render the printing mechanism inoperative without at the same time interfering with the continued passage of the strip material through the printing machine, or interrupting the flowing of the ink to and scraping of ink from the gravure rollers.

The mechanism provided for rendering the individual driving support rollers inoperative consists, in each case, of separate cams which are controlled by solenoid actuated pneumatic cylinders. Features of the invention consist in the provision of electric control devices which may be simultaneously or individually operated in order to provide a selective control by means of which the driving support rollers may be thrown into and out of operation as a group, and by means of which any individual support

roller may be separated from the group, and may be thrown into and out of operation individually as desired.

The printing units, provided in accordance with the invention, include each a drive support roller mounted beneath the traveling web, and transfer and gravure rollers mounted above the traveling web, the arrangement of these rollers being such as to provide a rigid construction of the rollers to insure the making of an impression of even strength across the material which may run 12 feet more or less in width.

Ink is supplied by means of a novel ink supply system which is particularly adapted to furnish ink in the very large quantity required to the printing units, herein described, in which the gravure and transfer roller are mounted to print the up-turned side of the web which may be traveling at speeds up to or in excess of 400 linear feet per minute. The ink supply system includes a pan of novel and improved construction arranged to be inserted beneath the gravure roller and about the traveling web. In order to adequately ink the gravure roller which as above indicated may be traveling at high speed, a pressure system is provided by means of which ink is sprayed from a header onto the surface of the roller as it approaches the ductor blade which slopes downwardly from its line of contact with the surface of the gravure roller. The ink is drawn strongly upwardly against the underside of the ductor blade by the rapidly moving roller surface and forms a large pool of ink beneath the ductor blade. The existence of the pool of ink thus formed in combination with the pressure of ink against the gravure roller surface produced by the spray insures that all of the cells of the gravure roller surface are fully loaded with ink. The pan referred to is in the form of a shallow tray which extends beneath the gravure roller, beneath the header of the ink spray unit, and is further provided with drainage ducts of large cross sections which add substantially to the total ink storage provided by the pan. The spray unit and drainage canals referred to are connected to form an ink circulating system by means of which an excess of ink, which may be 15 times that actually used, is continuously sprayed against the rotating gravure roller.

A feature of the invention consists in an improved ductor blade assembly including devices for equalizing pressure upon the gravure roller along its length which may be 12 feet, more or less. Other features of the invention consist in the novel construction and arrangement of the roller supporting and actuating devices to provide for both lateral and longitudinal linear adjustment of the roller printing surfaces with relation to the traveling web in order to register accurately with one another the impressions made by the several printing rollers.

With the above noted and other objects in view as may hereinafter appear, several features of the invention consist also in the method, devices, combination and arrangement of parts hereinafter described and claimed which, together with the advantages to be obtained thereby, will be readily understood by one skilled in the art from the following description taken in connection with the accompanying drawings, in which

Fig. 27 is a supplementary diagram view on the electrical controls for the torque motor.

Referring to the drawings the multiple impression printing machine herein disclosed as embodying in a preferred form the several features of the invention comprises a web draw-in unit generally designated at A in Fig. 1 having a drive support roller and a cooperating pressure roller, a first roller printing unit designated at B, an associated drying oven C, a second roller printing unit D, an associated drying oven E, and a web draw-out unit, generally indicated at F, comprising a drive support roller and a cooperating pressure draw-off roller. These units are constructed and arranged to cause a web of material to be processed, which in the preferred form of the invention is floor covering material, to pass through the several units in a straight line run.

The several operating units of the machine referred to

are driven in synchronism with one another by means of a torque shaft 30 which runs along the full length of the machine at the rear side adjacent the floor level, and is connected through individual reduction gear boxes with each of the separate units. The torque shaft 30 is continuously driven from any convenient source of power which may be an electric motor not shown.

Draw-in unit

The web draw-in unit A, above referred to, as best shown in Figs. 3 and 6 comprises a front standard 36, and a rear standard 38 supported on a base member 39 and rigidly connected by a spacer member 40. The standards provide support for two vertically slidable bearing blocks 42, 44 for a drive support roller 46. The standards also provide support for two bearing blocks 48, 50 (Figs. 3 and 6) for a pressure roller 52 which forms the upper roller of the pair. The drive support roller 46 is driven from the torque shaft 30 through a gear box 54, and a drive shaft 56 which extends from the rear to the front side of the machine slightly above the level of the base member 39. At its forward end the shaft 56 is provided with a bevel gear 58 which meshes with a bevel gear 60 forming the driving element of a differential gear unit generally indicated at 62, and is secured to a vertically disposed drive shaft 64 of said unit. The elements of the differential unit also include a bevel gear 66 which is secured to the shaft 64 and is connected by two idler bevel gears 68 with a driven bevel gear 70 mounted on a driven sleeve 72 in vertical alignment with the drive shaft 64. A bevel gear 74 keyed to turn with and slidable axially on the sleeve 72 meshes with a large bevel gear 76 which is mounted to turn as a unit with the drive support roller 46. A lug 79 formed integrally with bearing block 42 engages beneath and supports the bevel 74 in mesh with gear 76 for any vertical adjustment of the bearing blocks 42, 44 and driving support roller 46. The control element of the differential gear unit comprises an upwardly extending control shaft 80 which is mounted above and in axial alignment with the drive shaft 64 and which extends upwardly through an axial bore in the driven bevel gear 70 and sleeve member 72. At its lower end the shaft 80 is provided with a transverse bearing pin 82 on opposite ends of which are mounted the idler bevel gears 68 of the differential unit. With this arrangement it will be understood that rotation of the control shaft 80, causing the idler bevel gears 69 to rotate about the axes of the driving and driven bevels 66 and 70 has the effect of changing the angular relation of the driving roller 46 to the main driving connections including torque shaft 30. Thus a continuous rotation of the control shaft 80 of the differential gear unit in one direction will cause the driving roller 46 and associated pressure roller 52 to be continuously driven at a slower rate than that which would normally be imposed thereon by the main driving connections including torque shaft 30.

In accordance with the invention a torque driving motor is employed in combination with the differential driving connection above described to produce a regulated retarding tension or drag upon that portion of the webbed material, passing between the draw-in rollers 46, 52 and the draw-off rollers 152, 154. The amount of drag, which is in effect a braking force exerted on the traveling web is readily controlled by well known electrical means for adjusting the driving torque of the torque motor unit. The mechanism for producing a tensioning drag on the webbed materials specifically shown in Figs. 3, 4 and 5 comprises an electric torque motor 84 mounted on a bracket 86 on the front standard 36 of the draw-in unit A. The motor unit includes a transversely extending jack shaft 88 which is driven by means of reduction gearing from the armature shaft of the motor 84. A sprocket 90 on the shaft 88 is connected by a sprocket chain 92 with a sprocket 94 on a worm shaft 96 which is in turn

connected through a worm and gear connection 98 with the upper end of the differential gear unit control shaft 80. The torque motor unit operating through the differential gear unit as above described is employed to impose a drag on the webbed material being drawn through the printing machine. The manner in which this mechanism operates to carry out the objects of the invention will be more fully set forth hereinafter in connection with the description of the operation of the machine.

An individual manual adjustment is provided for each of the bearing blocks 48, 50 to control the position of the pressure roller 52 with relation to the drive support roller 46. Vertical adjustment of each of the blocks 48, 50 is effected by means of a rotatable sleeve element 100 (Fig. 6) which is externally threaded to a nut 102 fixedly supported on the respective front and rear standards. The sleeve element 100 is supported to turn on an upwardly extending shaft 104 secured at its lower end to the bearing block. A manually adjustable hand wheel 106 is secured to the upper end of the sleeve. A locking nut in the form of a second hand wheel 108 is threaded to the sleeve above the nut 102. For details of this construction reference can be had to the disclosure in Fig. 12 of an identically similar manual adjustment for the transfer roller of the first printing unit.

In accordance with the invention the drive support roller 46 together with the drive support rollers for each of the draw-off unit and the two printing units herein-after to be described are arranged and supported to be dropped downwardly out of engagement with the cooperating rollers at the upper side of the traveling strip in order to arrest the feed of the strip without interfering with the continued drive of the several rollers including the elements of the printing units. The mechanism provided for controlling the position of the drive support roller 46 comprises a rock shaft 110 (Fig. 3) which extends parallel to and beneath the drive support roller and which is supported in bearings in the respective standards 36, 38. Adjacent each end, the rock shaft 110 carries a cam member 112 which acts when the shaft is rocked in a counterclockwise direction as viewed from the front of the machine, to engage against and raise the respective bearing blocks 42, 44 and thereby to raise and to lock the drive support roller 46. For controlling this rocking movement of the rock shaft 110, a pneumatic cylinder 114 is provided which is supported at its lower end on a bracket 116 on the base 39. A piston element 118 extending from the upper end of the cylinder is connected with a lever arm 120 secured to the rock shaft 110. As indicated in Figs. 3 and 25 the cylinder 114 is provided at its lower end with an electric solenoid operated valve which controls the admission and exhaust of air to and from the cylinder.

Draw-off unit

The strip draw-off unit F, above referred to, as best shown in Figs. 1, 2 and 8, comprises a base 140 on which is mounted a front standard 142, (see Fig. 1) a rear standard 144, (see Fig. 8) and a spacer member, not specifically shown, by means of which the standards are rigidly secured together. Each standard is provided with a vertical guideway 146 to receive a vertically slideable bearing block, not specifically illustrated, for a web draw-off driving roller 152. A cooperating pressure draw-off roller 154 is similarly mounted for vertical adjustment in the standards 142, 144 in bearing blocks 156, supported for vertical movement in guideways formed in the upper part of the respective standards. For effecting this adjustment each bearing block 156 is provided with an upwardly extending shaft 159 providing support against axial movement relative thereto for a rotatable sleeve element 160 which is externally threaded to a nut 162 fixedly supported on the standard. A manually adjustable hand wheel 164 is secured to the upper end of

the sleeve, and a lock nut 166 similarly formed with a hand wheel is threaded to the sleeve above the nut 162.

The web draw-off drive support roller 152 is normally maintained in a relatively raised operating position in engagement with the cooperating pressure roller 154 and is further adapted to be moved from engagement therewith to release the web from feeding engagement therewith by a pneumatically operated device identical with that shown in Fig. 3 for the draw-in unit and which, as shown in Fig. 8, includes a rock shaft 168 which extends parallel to and beneath the drive support roller and which is supported in bearings in the respective standards 142, 144. Adjacent each end the rock shaft 168 carries a cam member 170 which acts, when the shaft is rocked in a clockwise direction as viewed from the rear of the machine, to engage against and to raise the respective bearing blocks for drive support roller 152, and thereby to raise and to lock the drive support roller 152 in its raised operative position. For controlling this rocking movement of the rock shaft 168 a pneumatic cylinder 172 is provided which is pivotally supported at its lower end on a bracket 174 on the base 140. A piston element 176 extending from the upper end of the cylinder is connected with a lever arm 178 secured to the rock shaft 168. As indicated in Fig. 25 the cylinder 172 is provided at its lower end with an electric solenoid operated valve 572 which controls the admission and exhaust of air to and from the cylinder.

The draw-off driving and pressure rollers 152, 154 are driven from the torque shaft 30 of the machine through operating connections (see Fig. 8) which include a reduction gear unit 180 having a vertically disposed output shaft 182 to the upper end portion of which is keyed a bevel gear 184 which meshes with a bevel gear 186 secured to the rear end of the web draw-off driving roller 152. A supporting lug 188 on the bearing block 150 is arranged to maintain the bevel gear 184 in mesh with the gear 186 for any adjustment of the blocks 148, 150.

First roller printing unit

The two roller printing units indicated at B and D in Fig. 1 which are supported and arranged to impart successive impressions registered with relation to one another to the webbed material during the run between the draw-in roller unit A and the draw-out unit F are with the only slight differences, hereinafter specifically pointed out, identical in construction. Referring specifically to Figs. 9 to 17 inclusive, the first printing unit designated at B comprises generally a fixed base assembly (see Fig. 9) including a base 200, a front standard 202, a rear standard 204, and a spacer member 206, and a relatively movable upper assembly in the form of a carriage 210 which is supported for forward and back movement transversely of the feeding web on guideways 208 formed in the upper ends of the respective standards 202, 204. The operating parts of the first printing unit include specifically a driving support roller 212 (see for example Figs. 9 and 12) which is mounted beneath the traveling web in the standards 202, 204 and a roller printing mechanism which is supported above the traveling web on the carriage 210. This mechanism comprises a transfer roller 214 mounted on the carriage directly above the driving roller 212, a cooperating gravure roller 216 which is mounted at that side of the transfer roller with the draw-in unit A and slightly above the transfer roller. The transfer roller 214 and gravure roller 216 are maintained at all times in continuous rolling contact in the carriage. An ink reservoir 218, and a ductor blade 220 also are mounted on the carriage 210. The drive for the transfer and gravure rollers 214, 216 of the first printing unit A is taken from the torque shaft 30 through a reduction gear box 222 onto a driving shaft 224 which extends between the rear and front standards 202, 204 slightly above the level of the base 200. A vertically disposed power output shaft 226 from

the gear box 222 at the rear side of the machine has splined thereto adjacent its upper end a bevel gear 228 which meshes with a bevel gear 230 secured to the rear end of the driving support roller 212.

A control mechanism is provided, similar to that described in connection with the driving support rollers for the draw-in and draw-out units, which is operative to move the drive support roller 212 vertically between a raised operative and a low inoperative position. To this end the support roller 212 is supported at each end in bearing blocks 232, which are vertically movable in guideways formed in the respective front and rear standards 202, 204. Vertical movement of the bearing blocks 232 and driving support roller 212 is effected by means of a rock shaft 236 which is mounted from the standards 202, 204 beneath and parallel to the support roller 212. Toward each end, the shaft 236 has secured thereto a cam 238 which engages beneath the respective bearing blocks 232. Movement of the rock shaft in a counterclockwise direction as viewed from the front of the machine causes the bearing blocks to be engaged by high portions of the respective cams to raise the support driving roller 212 to its driving position. For rocking the shaft 235 there is provided a pneumatic cylinder 240 which is pivotally connected at its lower end to a bracket 241 on the base 200.

A piston 242 extending from the upper end of the cylinder is connected to a laterally extending lever arm 244 secured to the rock shaft 236 for controlling the admission and exhaust of air from the piston. A solenoid controlled air valve 572 hereinafter described and shown in Fig. 25 controls the admission and exhaust of air from the cylinder.

The transfer roller 214 and the gravure roller 216 are positively driven at the same linear rate with the drive support roller 212. The drive is taken from the torque shaft 30 and reduction gear box 222 through driving shaft 224 to the front side of the machine, thence through bevel gears 248, 250 onto a vertical drive shaft 252. At its upper end the shaft 252 is fitted with a bevel gear 254 which meshes with a bevel gear 256 formed integrally with a large spur gear 258 which is supported to turn in a fixed bearing 260 provided in the upper portion of the front standard 202. A gear 262 (see Fig. 10) secured to the forward end of the transfer roller 214 meshes with the spur gear 258 and also with a gear 264 secured to the forward end of the gravure roller 216. The spur gear 258 is of substantial width so that the transfer roller drive gear 262 will always be meshed with the spur gear 258 irrespective of the transverse adjustment of the carriage 210.

First printing unit carriage

The carriage 210 on which the several elements of the printing unit are mounted comprises two end brackets or castings 266, 268, each formed with guides to engage with the guideways 208 on the respective front and rear standards 202, 204. The end castings 266, 268 are rigidly secured together by a connecting member, including specifically a heavy reinforced rail 270 (Figs. 11, 14, and 15) which carries a ductor blade assembly, hereinafter to be described. The transfer roller 214 is supported on the carriage 210 in bearing blocks 272 (Fig. 12) which are vertically adjustable in guideways 274 in the respective carriage end castings 266, 268. Individual adjustment of these bearing blocks is obtained by means of manually adjustable connections, including a central shaft 275 secured to the bearing block 272 having an externally threaded sleeve 276 supported against axial movement on the shaft 275, and rotated by means of a hand wheel 277. The sleeve 276 is threaded into a fixed nut formed in the end bracket 241 and is adapted to be locked in position by means of a locking nut which is actuated by a locking hand wheel 278. Inasmuch as the construction and arrangement of this screw and nut adjusting and locking mechanism is identical with that previously described for adjusting the position of the pressure roller 232 and 154,

no further description of these parts is believed necessary.

The gravure roller 216 is supported at each end in bearing blocks 280 which are mounted in guideways 282 (see Fig. 10) in the respective carriage end castings 266, 268 for adjustment in a horizontal plane toward and away from the impression transfer roller 214. This adjustment is effected simultaneously for both ends of the gravure roller through connections Figs. 10, 11, 12 and 13 which include a control shaft 284 which extends across the width of the machine being supported at one end in a bracket 286 on the end casting 266 of the carriage, and on its other end on a bracket 288 on the end casting 268. The control shaft 284 is connected near its forward end by bevel gears 290 with a vertically disposed worm shaft 292 which acts through a worm and worm gear 294 to rotate a screw threaded bearing block adjusting shaft 296 (Figs. 10 and 11). The shaft 296 is connected with the bearing block 290 carried on the end casting 266. The position of the rear bearing block is simultaneously and identically controlled from the control shaft 284 through operating connections which include bevel gears 298, a worm shaft 300, a worm and gear connection 302, and a bearing block adjusting screw 304. The adjustment described can be made manually from the rear side of the machine by means of a hand wheel 306 (Fig. 12) mounted on the control shaft 284 or from the front of the machine, if desired, by means of a hand wheel 308 (Fig. 10) mounted on the front end of control shaft 284.

Adjustment of the carriage 210 in a forward and back direction across the width of the feeding web is effected by means of an adjusting screw which is adapted to be manually operated by means of a hand wheel 316 (see Fig. 5), normally disconnected through the disengagement of an actuating clutch 314. This mechanism for effecting transverse adjustment of the carriage associated with the first printing unit is not specifically shown but is similar to that hereinafter described and more specifically illustrated in Figs. 13 and 14 for controlling the transverse position of the carriage 510 of the second printing unit.

40 A feature of the invention consists of the construction and arrangement of each of the printing units, whereby the impression roller and impression transfer roller are mounted above the feeding web so that the several colors of the design are applied to the upper side of the web. 45 This procedure has the advantage that the operator can at all times observe the progress and quality of the printing operation, and provides a most efficient arrangement of the web and ink spread thereon for drying. This arrangement, however, has been found to present a difficult problem to control and to maintain an accurate and even flow 50 of ink to the surface of the feeding strip, and to prevent leakage of ink with consequent blotting of the printed surface.

Features of applicant's construction which contribute 55 particularly to the efficient operation of the printing mechanism include a construction and arrangement of the support driving roller, impression transfer roller, and gravure roller which will provide a maximum support and rigidity of construction, of these rollers, well adapted 60 for producing an accurate impression over any desired width of material up to and including 12 feet or more. Another feature consists in the construction and arrangement of the ink supply system which includes an ink spraying device by means of which ink in considerable 65 volume is sprayed against the gravure roller, the excess being stripped from the surface of the roller by the ductor blade, collected in a shallow pan interposed beneath the gravure roller and spray header, and returned through drainage ducts to supply. Other features relate to a 70 novel construction and arrangement of the ductor blade and its supporting and actuating mechanism to remove all excess ink from the roller, and at the same time to insure an even application of ink to the transfer roller and to the surface of the material.

75 The roller printing units provided in accordance with

the present invention are well adapted for imparting an impression to a web of paper base or similar material while stretched taut in a flat straight line run so that substantially all of the natural elasticity of the material has been removed. The cooperating supporting and printing rollers are required to be of such length as to span a web, which may be 12 feet more or less in width, without any tendency to sag which would produce uneven or faint printing impressions particularly across the middle of the web. With the illustrated construction the necessary rigidity is obtained by a novel arrangement of the printing mechanism in which a driving support roller of sufficient size and strength, to ensure the desired rigidity, is located beneath the traveling strip, the cooperating transfer roller is located above the traveling strip in position to be supported along its full length by the driving support roller, and the gravure roller is mounted slightly above the level of the transfer roller where, because of the direction of rotation, the gravure roller will be in turn supported along its length by the transfer roller.

As shown in Figs. 15, 16 and 17 the ink supply system, for the printing unit, comprises a reservoir or trough in the form of a copper pan 218 having an arcuate trough 332 extending beneath and along the length of the gravure roller 216. The pan is formed at the side away from the transfer roller 214 with raised lateral extension 334 which receives the longitudinally extending header 335 and feeding pipes 336 thereto from which ink is sprayed onto the gravure roller. The pan is also provided, toward each end thereof, with a rectangular outlet duct 338 which extends laterally beneath the lateral extension 334, and thence to the front and rear sides of the machine respectively to downwardly extending exhaust ducts 340. The pan is rigidly secured in place on the carriage by suitable means. Ink is supplied to the ink spray header 335 from the front of the machine through an inlet pipe 342 which extends across the machine at the side of the pan away from the transfer roller and has secured thereto, at intervals, the feed pipes 336, above referred to, which connect with the header 335 in the extension 334 of the pan. The ink is drained through exhaust 340 to a reservoir 243 from which it is again forced into the inlet pipe 342 under pressure by means of a circulating pump designated at P in Fig. 16.

The operation of the inking device is briefly as follows:

The ink is supplied under pressure to the header 335 which is provided, at intervals, with orifices through which the ink is sprayed under pressure against the surface of the gravure roller. The impact of the ink streams causes the ink to be spread evenly over the surface of the gravure roller and has a strong tendency to force the ink into the cells which make up the ink transfer surface. The ink is drawn upwardly against the underside of the ductor blade which slopes downwardly from its point of contact with the peripheral surface of the roller to provide a pocket in which a relatively large pool of ink forms, thus still further tending to distribute and force the ink into the surface of the gravure roller. In order to obtain adequate inking of the roller at the relatively high speeds of printing made possible with the present machine which may be in the order of 400 feet, more or less, per minute it has been found necessary to supply through the ink pressure supply system a substantial excess of ink beyond that which is actually consumed by the printing operation, this excess being in the order of 15 times the amount of ink used. The excess is returned downwardly to the arcuate portion 332 of the pan 218, then flows outwardly through the exhaust ducts 340 to the supply reservoir 343. It has been found that a pool of ink forms beneath the ductor blade which is, more or less, proportional in size to the rate of linear movement of the roller surface. The excess ink provided finds its way downwardly into the pan and is drawn off through the exhaust ducts 340 above referred to. It will be understood that the ducts 340, together with the portion of the pan extending beneath the

gravure roller and spray header 335, are constructed and arranged to provide sufficient ink storage to take care of the large return which follows the disintegration of the pool of ink built up beneath the ductor blade when the drive of the gravure roller is arrested.

Ductor blade assembly

The ductor blade assembly, as best shown in Figs. 12, 13, 14 and 15, comprises a support shaft 346 which extends along the length of the printing unit and is supported for sliding movement on the rail 270 by means of guide brackets 348 which are supported at intervals to slide on the rail 270 and to which the support shaft 346 is rigidly secured. The support shaft 346 and the guide brackets 348, together, form a carriage on which the ductor blade 220 is supported for lengthwise oscillatory movement. The ductor blade is secured in a holder 352 (Fig. 15) in the form of a flat holder plate extending along the length of the printing unit and a cover member 354 by means of which the ductor blade is rigidly clamped in position. The holder 352 is supported by means of support arms 356 pivotally mounted at intervals from the support shaft 346 so that the ductor blade is permitted to swing freely to and from an engaging position against the impression roller 216.

In accordance with the present invention a novel and improved mechanism is provided for controlling the movement of the ductor blade into and out of engagement with the impression roller 216 and for maintaining an accurately controlled pressure of the ductor blade against the impression roller along the entire length of the unit. To this end a series of electrically controlled pneumatic cylinders are provided which are spaced along the length of the ductor blade slide and are connected to control the swinging movement of the ductor blade about the support shaft 346.

In the illustrated form of the invention five of these cylinders are provided including a centrally located cylinder 358 (Fig. 14) which, as hereinafter described, is a double acting braking cylinder, and four additional cylinders 360 which are employed primarily to maintain a required even pressure of the ductor blade against the impression roller along the full length of these parts. Each of the cylinders 358 and 360 is mounted on an upwardly extending arm 362 formed integrally with a respective guide bracket 348. Each cylinder is provided with a piston 364 which is pivotally secured to a lug 366 formed integrally with pivoted support arm 356. Each cylinder is provided at its upper end with a solenoid operated valve control, by means of which the supply and exhaust of air to each of the cylinders is readily controlled. When air pressure is applied the four end cylinders 360 tend to force the ductor blade 350 against the impression cylinder 216. This action is, however, retarded by the operation of the centrally located double action cylinder 358 which acts to retard the downward movement of the ductor blade, and thus to prevent possible marking of the copper impression cylinder. Upon actuation of the solenoid control valves to reverse the flow of air to all of the cylinders, the ductor blade is moved rapidly to an inoperative limited position.

During the operation of the machine the ductor blade 220 is oscillated back and forth in a lengthwise direction to eliminate any possibility of scratching and to further assist in maintaining an even regulated flow of ink from the impression roller onto the transfer roller 214.

The oscillating mechanism, as best shown in Figs. 12 and 13, comprises an eccentric 368 which is mounted at the rear end of the carriage on a bracket 370, fixed to the end casting 268, and is connected by an eccentric arm 372 with a guide bracket 348 secured to the rear end of the ductor blade support shaft 346. The eccentric is conveniently driven from a small motor 374 (see Figs. 13 and 18) through a belt and pulley drive 376 which connects with the input shaft 378 of gear box 380, the

eccentric 368 being mounted on the output shaft 382 of this reduction gear box mechanism.

Second printing unit

The second printing unit designated at D in Fig. 1, and more specifically shown in Figs. 7 and 18 to 20 inclusive, is substantially identical with the printing unit B, previously described, except for the provision of a novel means for securing an accurate register of the impression produced thereby on the traveling sheet of webbing longitudinally as well as laterally with relation to the impression produced on the sheet by the first printing unit B. The second printing unit comprises a base assembly including a base 400, a front standard 402, and a rear standard 404, and an additional spacer member 406 for maintaining these parts rigidly in position. A driving support roller 408 is mounted in the base assembly of the printing unit, being supported in bearing blocks 410 mounted for vertical adjustment in the respective front and rear standards. A control mechanism is provided for shifting the driving support roller 408 between a high operating and a low inoperative position which is similar to that previously described for effecting a similar shift between high and low positions of the first printing unit drive support roller 212. This mechanism includes a rock shaft 412 having at each end cams for engagement beneath the bearing blocks 410, and a solenoid controlled pneumatic cylinder 414 for controlling the position of the rock shaft.

The second printing unit D further comprises a carriage 416 mounted on guideways on the respective standards for movement transversely of the feeding strip. The carriage provides support for a transfer roller 418 mounted directly above the driving support roller 408 and a gravure roller 420 mounted at that side of the transfer roller with the draw-in unit A and at a level slightly above that of the transfer roller. The second printing unit is also provided with a ductor blade assembly including a ductor blade, not shown, with air control cylinders 421 and braking cylinder 423 (see Fig. 24), and an ink supply system.

Inasmuch as the construction and arrangement of the carriage 416, the gravure roller 420, and transfer roller 418 together with the supporting devices therefor, the ductor blade assembly and ink supply devices are in all respects identical with the corresponding parts of the first printing unit above described, a further detailed description or illustration of these parts is believed unnecessary and will be omitted.

The drive support roller 408 for the second printing unit is driven from the torque shaft 30, through a gear box 430 and vertical output shaft 432, having a bevel gear 434 splined thereto for engagement with a bevel gear 436 mounted from the rear end of the drive support roller 408.

The drive for the transfer roller 418 and gravure roller 420 of the second printing unit is taken from the gear box 430 through a horizontally disposed drive shaft 438 to the front side of the machine, and through bevel gears 440, 442 to the input shaft 444 of a vertically disposed differential gear unit 446 similar to that illustrated and described for driving the drive support roller of the draw-in unit above described. The unit includes driving and driven bevel gears 445, 447 connected respectively to input shaft 444 and an output sleeve 448, and two interposed idler bevel gears 449. The output sleeve member 448, from the unit aligned with the input shaft 444, carries a bevel gear 450 which meshes with a bevel gear 452 formed internally with a large spur gear 454 which in turn meshes with a driving gear 456 secured to the forward end of the transfer roller 418. The gear 456 meshes also with a driving gear 458 on the gravure roller 420.

The control element of the differential gear unit 446 comprises a shaft 460 disposed within the driven sleeve

448 and having at its lower end a cross shaft which carries the two idler bevel gears 449 disposed between and meshing with the axially aligned driving and driven bevel gear elements 445, 447 of the unit.

5 In accordance with the invention the differential unit above described is employed to effect an angular adjustment of the second printing unit transfer roller 418 and gravure roller 420 with relation to the driving mechanism for the machine, and thereby to obtain an adjustment of the impression imparted to the feeding web longitudinally thereof.

As shown in Figs. 19 and 20, a worm gear 470 secured to the upper end of the control shaft 460 is in mesh with a worm 472 on a hand wheel supporting shaft 478. A 15 hand wheel 480, loosely supported to turn on the shaft 478, is arranged to be connected therewith by means of a clutch 482. A compression spring 484 tends normally to maintain the hand wheel in an extended inoperative position.

20 In accordance with another feature of the invention the mechanisms, above described for adjusting the first printing unit laterally, and for adjusting the second printing unit both laterally and longitudinally with relation to that portion of the webbed material stretched between 25 the draw-in and draw-off roller units, are adapted for automatic control by scanning devices to maintain an accurate register of the printing units with one another to produce an accurate clean cut pattern in the traveling web. The scanning device, by means of which the 30 angular (longitudinal) adjustment of the second printing unit is made, is of a type well known in the art and comprises a so-called electric eye which operates through suitable electronic devices to operate a small reversible electric motor 488 (see Fig. 7) which is connected 35 through reduction gearing, a sprocket chain 490, a driving sprocket 492, and a driven sprocket 494 on the hand wheel supporting shaft 479. The electric eye acts with relation to a recurring mark placed on the margin of the webbed material by the first printing unit in the event 40 that the printing unit is not properly registered with the mark to drive the electric motor 488 in one direction or the other, and thereby to adjust the angular portion of the transfer roller 418 and gravure roller 420 so that the impression imparted by these rollers registers longitudinally with the impression of the first printing unit 45 on the traveling web.

A similar scanning device is provided for effecting an automatic lateral adjustment of the carriage 416 with the transfer roller 418 and gravure roller 420 supported 50 thereon. This mechanism comprises an electric eye which acts through suitable electronic devices, not specifically shown, and an electric motor 500 connected through reduction gearing, a sprocket chain 502, a driving sprocket 504, and a driven sprocket 506 with a lateral adjusting shaft 508. The shaft 508 is supported to turn in a bearing formed in a bracket 510 on the front standard 402, and at its rear end is in threaded engagement with a nut 511 mounted on carriage 416. Lateral adjustment of the printing unit is effected manually by means of a hand 55 wheel 512 splined to the shaft 508. The electric eye acts with relation to a recurring mark placed on the margin of the web material by the first printing unit to operate the electric motor in one direction or the other as required, and thereby to effect by automatic means any 60 necessary lateral adjustment of the carriage and rollers 416, 418 mounted thereon.

In a machine of the type illustrated in which a plurality of printing impressions or coatings may be applied in succession to a rapidly traveling web, the rapid drying 70 of the ink and the control of the web in such a manner as to avoid blurring during this drying process, is a matter of great importance. A feature of the invention consists in the construction and arrangement of the printing machine so that the web is supported in a horizontal 75 position with the printed side up to facilitate successive

printing and intermediate drying operations during the run of the web between the draw-in and draw-off roller units. As shown in Figs. 21, 22 and 23 of the drawings, the drying unit designated at C associated with the first printing unit, comprises an oven 530 which is generally rectangular in shape, extending approximately 10 feet from the first to the second printing unit, and having the top portion thereof sloping downwardly to the front side of the machine. Hot air is supplied to the oven 530 through an inlet duct 531, blower 532 and heating unit 533, being directed forwardly over the web through a chamber 534 formed in the upper half of the oven, and then downwardly in jets against the upper side of the traveling web through narrow openings 536, each of which is formed with a deflecting plate 538. Air is exhausted from the underside of the oven through an exhaust duct 540 to which is connected an exhaust fan 541. The heating unit E, associated with the second printing unit D, is identically similar in construction comprising an oven 542 to which hot air is supplied through a hot air duct similar to that supplying the oven 530, but not shown, and from which the air is exhausted through exhaust duct 540. Inasmuch as the details of the two drying units C and E form specifically no part of the invention, further description thereof is believed unnecessary.

The web is supported during its passage through the ovens on guide bars and plates which, as shown in Fig. 23, include three spaced bars 543, and two interposed plates 544 which are located slightly below the level of the traveling web.

The illustrated machine is provided with electrical devices under the control of the operator for controlling the operation of the air cylinders, above described, by means of which the several drive support rollers are lowered and raised, and for controlling the air cylinders by means of which the ductor blades are moved into and out of operating engagement with the respective gravure rollers. Provision is made for controlling individually the operation of the ductor blade associated with each printing unit, as shown in the diagrammatic Fig. 24. The electrical devices for moving the ductor blade associated with the first printing unit, into and out of operating position, comprise a series of solenoid operated air valves 546 mounted integrally with each of the ductor blade actuating cylinders 360 and braking cylinder 358.

Each solenoid air valve 546 is provided with raise and lower control leads marked respectively as R and L, and an intermediate terminal 548. Each of the terminals 548 are connected in parallel to a wire 550 of a two-wire system connected with a power supply transformer 552. The R terminals are connected in parallel to a wire 554 which is in turn connected through a manually operable push button switch 556 with a wire 563 connected to the power supply transformer 552. The L terminals are connected in parallel to a wire 560 which is in turn connected through a manually operable push button switch 562 with said wire 563 connected to the power supply transformer 552.

The electrical devices for controlling the operation of the second printing unit are similar to those above described for controlling the ductor blade assembly associated with the first printing unit. Each of the ductor blade operating cylinders 421, 423, associated with the second printing unit, are provided with a solenoid air valve 564 having raise and lower control positions, and arranged to be controlled by normally opened raise and lower push button switches 566, 568 which are connected with the two wires 558, 563 from the power supply transformer 552.

The operation of the ductor blade control devices is as follows:

Assuming that the ductor blade is in its raised operative position the operator pushes the lower push button, switch 556 associated with the first printing unit, thereby

de-energizing the solenoids, and thereby con-

ditioning the valve units to admit air to each of the cylinders 360 and 358 to move the ductor blade against the gravure roller. The air valves remain in their open positions so that air is supplied continuously to the air cylinders to maintain an evenly distributed pressure upon the ductor blade against the gravure roller. As previously noted the cylinder 358 is of the so-called double-acting type and acts as a brake to slow the rate of movement of the blade against the roller to prevent possible marking or injury thereto. When it is desired to move the ductor blade to its inoperative position the operator will press the raise push button 562 to energize the R solenoids, and thereby to condition the air valves to exhaust air from the cylinders 360 and to reverse the flow of air to the cylinder 358. The ductor blade now moves upwardly in response to the action of the double acting cylinder 358 to a high inoperative position.

In accordance with the invention control devices are provided which enable the operator to move the drive 20 support rollers, associated with the several operating units of the machine either as a group or individually, between raised operating and lowered inoperative positions in which they are separated from the cooperating pressure and impression transfer rollers.

25 The electrical devices provided for controlling the operation of the several air cylinders by means of which the respective driving support rollers are raised and lowered comprise a series of solenoid operated air valves 572 mounted integrally with each of the driving support roller 30 raising and lowering air cylinders 114, 172, 240 and 414. Each solenoid air valve 572 is provided with raise and lower control leads marked respectively as R and L, and an intermediate terminal 574. Each of the terminals 574 is connected to a wire 576 which is connected to a power 35 supply transformer 578. The R terminals are connected respectively by identical wires 580 with one terminal of a manual-automatic control switch 584. An extension of the R line 580 is connected with a normally opened push button control switch 588 which is in turn connected by 40 a wire 590 with the power supply transformer 578. The drive support roller drop control terminal L, from each of the solenoid actuated valves 572, is connected by means of a wire 592 through a micro-switch 594 with a second terminal 596 of the manual-automatic switch 584, and 45 also with a normally opened lower button control switch 598 which is connected by the wire 590 with the power supply solenoid 578. Since the electrical connections to each of the solenoid operated air valves 572 are identical, the same reference characters have been used for the 50 designation of these identical parts. Each of the several raise control switches 588 and lower control switches 598 are connected with the power supply transformer by a wire 600 and wire 590. Of two remaining terminals 602, 604 associated with each manual-automatic switch 584, the 55 terminals 602 are connected by wires 605 and 606 to a stop switch 607 which is connected to the power supply line 590 and transformer 578. The terminals 604 are connected by means of wires 608 and 610, and a Forward switch 612 to the power line 590 from the power supply 60 transformer 578.

The operation of the control devices for moving the several driving support rollers between operative and inoperative positions is as follows:

65 Assuming that all of the manual-automatic switches 584 are closed so that the several solenoid controlled air valves are directly controlled by the automatic Forward and Stop switches 612, 607, the pressing of the Forward automatic switch button 612 causes all the R solenoid 70 contacts to be energized shifting the air valves 572 to the raise position in which air is admitted to the several air cylinders 114, 172, 240 and 414 thus raising the several driving support rollers to operative position to feed the web through the machine. The several cylinder pistons, 75 upon reaching the limit of their upward movement, en-

gage with and close the respective micro-switches 594 so that the electrical circuit including the drive support roller drop control terminals may be energized by the actuation of either the automatic manual stop switch 607 or the individual stop switch 598.

In order to stop the feed of the web the operator presses the Stop button 607 causing the L contacts of the several solenoid controlled air valves 572 to be energized to condition the respective air valves to exhaust air from the respective air cylinders 114, 172, 240 and 414. The downward movement of the pistons causes each of the driving support rollers to be lowered to its inoperative position to arrest the feeding and printing operations without interference with the continued drive of the drive support rollers, and printing unit rollers.

The arrangement above described for stopping the feed of the web provides a convenient means available to the operator for stopping the machine with a minimum of disruption to the machine operation. The continued drive of the gravure and transfer rollers of the printing units, although the advance of the web is stopped, has the advantage that a continuous circulation and flow of ink through the printing unit is maintained which avoids any possibility that the ink will tend to dry or to harden on the rollers.

Whenever one of the manual-automatic switches 584 is shifted to its open position the associated solenoid control air valve 572 is operatively disconnected from the automatic switch control buttons 612, 616 and remains under the individual control of the manual forward and reverse buttons 588, 598 which will now control the movement of the drive support roller of said machine unit to and from its operative position. In the event that one of the printing units, as for example the first printing unit B, is to be rendered inoperative in this manner while a printing or lacquering operation is being carried on only by the second printing unit D the manual-automatic switch 584 associated with the first printing unit is moved to the open position as shown, and the reverse button 598 associated with the first unit is pressed causing the L contact of the solenoid air valve 572 to be energized thereby exhausting air from the air cylinder 240 and causing the drive support roller 212 to be moved downwardly to its inoperative position.

The individual controls for moving the respective drive support rollers between raised operative and lowered inoperative positions have been found useful also to condition the machine for various operations, as for the adjustment of the several rollers of the respective machine units when the machine is stopped, and for straightening any portion of the web which may have gotten out of line. The printing units may be rendered inoperative individually to avoid printing over defective or uneven portions of the web which might cause injury to the transfer roller surface.

The operation of the torque motor unit 84 to retard the rotation of the draw-in pressure and drive support rollers in order to tension the feeding web will be readily understood from an inspection of the electrical diagram of Figs. 26 and 27, of which Fig. 26 is a single line diagram of the electrical operating connections and Fig. 27 is a complementary diagram showing the positions of the several elements including the control switches and the supporting panels. Referring to Figs. 26 and 27 the torque motor 84 is shown having an armature 620, a commutator field 622 and a shunt field 624. The speed or torque of the motor is determined by the adjustment of a speed control 626 having a rheostat 628 and an adjustable arm 630 which is connected to the grid 632 of a thyratron tube 634 through which direct current is supplied to the armature and the commutator field winding of the motor. A further adjustment of the power input is effected by means of a variable speed generator 634 supported in series with the rheostat 628 of the speed control and arranged to be driven from the torque shaft

30 of the machine. There is also provided on the same panel with the speed control a start and stop switch 636 for the torque motor 84.

From an inspection of the single line diagram of Fig.

- 5 26, it will be noted that a direct current is supplied to the armature 620 and commutator field winding 622 through the thyratron rectifier tube 634 and that direct current is supplied to the shunt field 624 through a rectifier tube 638. The arm 630 of the speed control unit is connected with 10 the control element on grid 632 of the tube 634 by means of a wire 640 and resistance elements of ordinary construction. The rheostat 628 of the speed control 626 is connected to the variable speed generator 634 by a wire 642 and a suitable resistance unit. The generator 634 is 15 also connected with one of the two line wires indicated at 1. The arrangement of the several elements of the torque motor electrical circuit are such that the power output of the torque motor is held to a constant value which is determined by the setting of the control arm 630, 20 and is further controlled by the rate of drive of the main torque shaft 30 which in turn controls the rate of drive of the generator 634. It is the function of the generator 634 to vary the power output of the torque motor in proportion as the rate of feed of the web through the 25 printing machine is increased or decreased, so that the amount of stretch imposed on the web in accordance with the setting of control arm 630 will remain constant regardless of the speed at which the machine is driven.

The amount of drag exerted on the traveling web by the 30 torque motor 84 and differential connection in the drive to the draw-in rollers 46, 52 is readily adjusted during machine operation by manual adjustment of the speed regulator hand 630. As the torque is gradually increased any tendency of the web to weave will disappear and the 35 web will be found to be running true along the entire length of the run to the draw-off station. Under these conditions, in which a floor covering material which may be an asphalt impregnated felt or paper is passing through the machine a stretch of about $\frac{1}{8}$ " per linear yard may 40 be present. If the torque is increased beyond the elastic limit of the material it may be noted that the web tends to ripple, followed by separation and breakage of the web.

Features of the invention relating specifically to a 45 gravure printing couple for printing on a web with details of the printing couple appurtenances included have been made the subject matter of a divisional application entitled An Improved Machine for Printing Webs of Paper Base and Similar Fibrous Web Materials, filed in the United States Patent Office.

50 Features of the invention relating specifically to a novel and improved web feeding and control mechanism form the subject matter of a divisional application entitled An Improved Web Feeding and Printing Mechanism for a Multiple Unit Roller Type Printing Machine, 55 filed in the United States Patent Office.

Features of the invention relating specifically to means 56 for transverse and longitudinal register adjustment for a web printing couple associated with a conveyor system in which the web is passed through the printing couple 60 as a flat sheet while stretched to substantially its elastic limit forms the subject matter of a divisional application entitled Improved Register Producing Means for a Roller Printing Machine, filed in the United States Patent Office.

65 The invention having been described what is claimed is:

1. The method of processing paper base and similar 70 fibrous web materials having a low stretch characteristic which, when all stretch is removed therefrom, will not return to its original condition, which comprises the steps of conveying said web along a straight line run of substantial length between draw-in and draw-off stations, positively and continuously drawing off the web at the draw-off station at a predetermined linear rate, applying

at the draw-in station a stretch producing drag to the web and stretching the web only at the beginning of the run between said draw-in and draw-off stations by feeding said web into said run at a positively controlled lower linear rate than said draw-off linear rate at a constant differential selected to stretch said web substantially to the elastic limit to substantially remove all stretch from said stretched portion of the web while between said stations thereby providing a dead sheet free from longitudinal stretch and lateral weave variations, and during said straight line run rolling on at least some portions of the surface of the previously stretched web a liquid coating.

2. The method of processing webs of paper base and similar fibrous web materials having low stretch characteristics which, when all stretch is removed therefrom, will not return to its original condition, which comprises the steps of conveying the web along a straight line run of substantial length past a plurality of printing units between draw-in and draw-off stations, supporting the web at each of the draw-off and draw-in stations between pairs of draw-in and draw-off rollers, driving the draw-off rollers at a predetermined linear rate to draw the web along the length of the run, and driving the draw-in rollers at a linear rate lower than the linear rate of drive of the draw-off rollers at a predetermined constant differential selected to stretch said web substantially to the elastic limit to substantially remove all stretch from said stretched portions of the web passing between said stations providing a dead sheet free from longitudinal stretch and lateral weave variations, and at least one station along said run imparting an impression to the web synchronized and registered with relation to the traveling web.

3. The method of printing paper base and similar fibrous materials having a low stretch characteristic which, when all stretch is removed therefrom, will not return to its original condition, which comprises the steps of supporting the traveling web for movement in a straight line run of substantial length between draw-in and draw-off stations, drawing off the web at the draw-off station continuously and positively at a predetermined rate to draw the web along the length of the run, applying a stretch producing drag to the web at the draw-in station to draw the web into said run at a lower linear rate than said draw-off linear rate at a constant differential selected to stretch said web substantially to the elastic limit to substantially remove all stretch from said stretched portions of the web passing between said stations providing a dead sheet free from longitudinal stretch and lateral weave variations, and imparting simultaneously to separate portions of the web along said run a plurality of printing impressions synchronized and registered with relation to one another on the traveling web.

4. The method of roller printing webs of paper and similar fibrous web materials having a low stretch characteristic which, when all stretch is removed therefrom, will not return to its original condition, with a plurality of successive impressions in register with one another which comprises the steps of supporting the web at the two ends of a straight line run of substantial length between positively driven pairs of draw-in and draw-off driving rollers, driving the draw-off rollers at a predetermined rate to draw the web along the length of the run, driving the draw-in rollers at a linear rate lower than the linear rate of the driving of the draw-off rollers at a predetermined constant differential, selecting said differential to stretch said web substantially to the elastic limit to substantially remove all stretch from said stretched portions of the web passing between said stations providing a dead sheet free from longitudinal stretch and lateral weave variations, and operating roller printing devices in synchronism with one another at the same linear rate with said draw-off rollers at separated positions on

said run to produce impressions registered with relation to one another upon the traveling web.

5. A machine for processing webs of paper base and similar fibrous web materials having a low stretch characteristic which, when all stretch is removed therefrom, will not return to its original condition, which comprises devices for processing said web, and a web conveyor having draw-in and draw-off stations spaced to provide a straight line run of said web through the processing devices, draw-off means at the draw-off stations having a positive web feeding action to continuously draw-off the web at a predetermined linear rate, and means having a positive web feeding action for feeding said web into said run including means connected with said draw-off means for feeding said web into said run at a positively controlled lower linear rate than said draw-off linear rate at a constant differential selected to stretch said web substantially to the elastic limit to substantially remove all stretch from said stretched portion of the web passing between said stations thereby providing a dead sheet free from longitudinal stretch and lateral weave variations.

6. In a machine for processing continuously feeding webs of paper base and similar fibrous web materials having a limited stretch characteristic, which, when all stretch is removed therefrom, will not return to its original condition, the combination with devices for processing the traveling web at a plurality of processing stations, of a web conveyor including web draw-off devices comprising a pair of drive support and pressure rollers, a web draw-in device spaced from the draw-off device to provide a straight line run of substantial length of said web through said processing devices and comprising a pair of driving support and pressure rollers, driving means connected to drive each of said drive support rollers at the same linear rate, a device comprising a differential connection from said driving means through which the draw-in rollers are driven, and a torque motor connected with said differential connection to drive said draw-in roller at a selected constant lower linear rate than said draw-off roller, and means for adjusting said torque motor to regulate said lower linear rate of said draw-in rollers to stretch said web substantially to the elastic limit to substantially remove all stretch from said web providing a dead sheet free from longitudinal stretch and lateral weave variations.

7. A machine in accordance with claim 6 in which independent supporting means are provided for supporting each end of the draw-in pressure roller, and means are provided under the control of the operator for effecting an independent adjustment of each of said supporting means toward and away from the cooperating draw-in driving roller.

8. In a machine for processing continuously feeding webs of paper base and similar fibrous web materials having a limited stretch characteristic, which, when all stretch is removed therefrom, will not return to its original condition, the combination with a plurality of processing devices for imparting successive impressions registered with relation to one another to the traveling web, of a conveyor including a web draw-off device comprising a pair of drive support and pressure rollers, driving means for said rollers, a web draw-in device spaced from said draw-off device to provide a straight run of said web through said processing devices comprising a pair of driving and support rollers, and a differential connection from said driving means acting upon said draw-in rollers to positively retard said draw-in rollers for feeding said web into the run at a positively controlled lower linear rate than said linear rate of the draw-off rollers, to stretch said web substantially to the elastic limit to substantially remove all stretch of the web in said run, providing a dead sheet free from any longitudinal stretch and lateral weave variations, and means for adjusting said device to control the amount of stretch.

9. In a machine for roller printing webs of paper base and similar fibrous web materials having a limited stretch

characteristic, which, when all stretch is removed therefrom, will not return to its original condition, with a plurality of successive impressions in register with one another, the combination of a web conveyor having a pair of draw-off rollers including a drive support roller and a cooperating pressure roller, a pair of draw-in rollers including a drive support roller and a pressure roller spaced from the draw-off rollers to provide a straight line run of substantial length of the web therebetween, a plurality of printing units disposed along said run, each unit comprising a driving support roller, and a cooperating transfer roller and printing roller disposed above the web, driving means for driving all of said support rollers at the same linear rate, and a differential connection from said driving means acting upon said draw-in rollers to positively retard said draw-in rollers for feeding said web into the run at a positively controlled lower linear rate than said linear rate of the draw-off rollers, to stretch said web substantially to the elastic limit to substantially remove all stretch of the web in said run, providing a dead sheet free from any longitudinal stretch and lateral weave variations, and means for adjusting said device to control the amount of stretch.

10. In a machine for roller printing webs of paper base and similar fibrous web materials having a limited stretch characteristic, which, when all stretch is removed therefrom, will not return to its original condition, with a plurality of successive impressions in register with one another, the combination of a web conveyor having a pair of draw-off rollers and a pair of draw-in rollers spaced from the draw-off rollers to provide a straight line run of substantial length of the web therebetween, a plurality of printing units spaced from one another along said run for placing successive impressions registered with relation to one another on the feeding web, driving means for driving each of said draw-off rollers and printing units at the same linear rate, driving means for the draw-in rollers including a differential connection, a torque motor connected with said differential connection operative to reduce the rate of drive of the draw-in rollers, and means controlled from said driving means for controlling said torque motor to rotate the draw-in rollers at a lower stretch producing linear rate to substantially remove all elastic stretch from the web along the length of said run producing a dead sheet free from longitudinal stretch and lateral weave variations.

11. The combination as set forth in claim 10 further including means under control of the operator for adjusting said torque motor control.
12. In a machine for roller printing webs of paper base and similar fibrous web materials having a limited stretch characteristic, which, when all stretch is removed therefrom, will not return to its original condition, the combination of a web conveyor constructed and arranged to draw the web along a run lying substantially in a horizontal plane between draw-in and draw-off stations, a drive support roller beneath the web and a cooperating pressure roller above the web at each of said stations, a plurality of printing units disposed along the length of said run each comprising a drive support roller beneath the web, a cooperating impression roller, means for inking the impression roller above the web, and means for drying the ink, means positively driving each of said drive support rollers at the same linear rate, and a differential connection from said driving means acting upon said draw-in drive support roller for feeding said web into the run at a positively controlled lower linear rate than said drive roller linear rate, to stretch said web substantially to the elastic limit to substantially remove all stretch of the web in said run, providing a dead sheet free from any longitudinal stretch and lateral weave variations.

U. S. DEPARTMENT OF COMMERCE
PATENT OFFICE
CERTIFICATE OF CORRECTION

Patent No. 2,809,582

October 15, 1957

Earl A. Crawford

It is hereby certified that error appears in the printed specification of the above numbered patent requiring correction and that the said Letters Patent should read as corrected below.

Column 4, line 19, for "about" read --above--; column 14, line 37, for "shaft 479" read --shaft 478--; column 15, line 75, the line should read as follows instead of as shown in the patent --simultaneously energizing the solenoids, and thereby con- --; column 16, line 63, for "operative" read --operative--.

Signed and sealed this 25th day of March 1958.
